(57) **CLAIM**

We claim the ornamental design for a picture frame, as shown and described.

DESCRIPTION

FIG. 1 is a rear perspective view of a picture frame according to a first embodiment of our new design, wherein an easel of the picture frame is in a storage position;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view thereof, wherein the easel of the picture frame is in a use position;

FIG. 10 is a rear perspective view of a picture frame according to a second embodiment of our new design, wherein an easel of the picture frame is in a storage position;

FIG. 11 is a front perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a rear perspective view thereof, wherein the easel of the picture frame is in a use position.

The broken lines in the drawings illustrate portions of the picture frame that form no part of the claimed design.

1 Claim, 14 Drawing Sheets
